UNITED STATES PATENT OFFICE

123,539

DESIGN FOR A DRESS

Dorothy High, New York, N. Y.

Application September 3, 1940, Serial No. 94,789

Term of patent 3½ years

To all whom it may concern:

Be it known that I, Dorothy High, a citizen of the United States, residing in New York city, in the county of Manhattan and State of New York, have invented a new, original, and ornamental Design for a Dress, of which the following is a specification, reference being had to the accompanying drawing, forming part thereof.

Fig. 1 is a front view of a dress showing my design;

Fig. 2 is the rear view thereof; and

Fig. 3 is an enlarged fragmentary view of the

dress shown in Fig. 1 illustrating the sleeve embroidery in detail.

The characteristic feature of my design resides in the combination on the dress disclosed of the specific sleeve members which are embroidered as shown, in association with the intertwist on the blouse and the diamond-shaped girde, all as shown.

I claim:

The ornamental design for a dress, substantially as shown and described.

DOROTHY HIGH.
